ELECTRODE

William E. Good, Pittsburgh, Pa., assignor to
Westinghouse Electric Corporation, East Pitts-
burgh, Pa., a corporation of Pennsylvania

Application July 2, 1945, Serial No. 602,865

7 Claims. (Cl. 315—5)

1

My invention relates to electrical discharge devices and in particular to such discharge devices in which electrons of an electron beam are velocity-modulated in passing through a resonating chamber having conducting walls, and after exit from the chamber have their velocities reversed by a reflector electrode so that a substantial portion of them re-enter the chamber. Such an arrangement is capable of generating oscillations of extremely short wave length and may be termed a reflex type of ultra-short wave oscillator.

One object of my invention is to provide an improved type of reflector electrode which shall ensure the re-entry into the chamber of a greater fraction of the emerging electrons than did reflector electrodes of the prior art.

Another object of my invention is to provide a reflex oscillator having a reflector electrode of such form as to substantially increase the electrical efficiency of the oscillation generator.

Still another object of my invention is to provide an arrangement in which the configuration of the electric field between the reflector electrode and the outlet of the resonating chamber may be varied in form at will.

Still another object of my invention is to provide an arrangement in which the configuration of the electric field in the neighborhood of the reflector electrode may be regulated in accordance with the current or operating voltage of the reflex oscillation generator.

A still further object of my invention is to provide a reflex type of oscillation generator with a form of reflector electrode suitable for experimentally varying the configuration of the electric field in the region of the reflector electrode to determine the optimum form suitable for a tube of given current and voltage rating.

Other objects of my invention will become apparent upon reading the following description taken in connection with the accompanying drawings, in which:

Figure 1 is a diagrammatic view, largely a diametrical section, of an electrical discharge tube embodying the principles of my invention.

Figs. 2 and 3 are diagrammatic illustrations of reflector electrode arrangements alternative to the reflector electrode of Fig. 1, and

Figs. 4 and 5 are diagrams useful in explaining the application of the principles of my invention to reflex oscillator tubes.

Referring in detail to Fig. 1 of the drawing, there is shown a sealed glass envelope 10 having a reentrant stem 11 at one end thereof. The en-

2

velope, which is preferably evacuated, encloses an "electron gun" for producing a relatively concentrated beam of electrons. As shown here, the "gun" includes a cathode comprising a heater 13 surrounded by an emitting member 14. Electrons emitted by this cathode are accelerated to a desired velocity by means of an accelerating electrode structure 15 having a small opening 16 in its end through which a concentrated beam of electrons is projected through a grid or other form of opening 17 in the walls of a conducting resonator or chamber 18. On the opposite wall of the chamber 18 in line with the path of the electron beam passing through the opening 17 is positioned a second grid or other form of opening 19 through which the electrons of the beam may emerge from the chamber 18. A suitable voltage source 21 having its positive terminal grounded supplies heating current to the heater 13. A second voltage source 22 having its negative terminal grounded and connected to electrode 15 supplies current to a potentiometer 20 to a variable tap on which is connected the resonating chamber 18.

As is well known in the art, it is possible, by adjusting the electrical potential at the opening 17 by means of the associated slider on potentiometer 20, to give the electrons entering through opening 17 into chamber 18 such a velocity that they will consume in passing from the opening 17 to the opening 19 one-half period of the natural frequency of electrical vibration of the resonant chamber 18. When this is done, those electrons which enter the opening 17 when the electrical field of chamber 18 has such a direction as to accelerate them, will leave the opening 19 one-half a cycle later when the electrical field at opening 19 tends likewise to accelerate them and will accordingly undergo a net increase of velocity in passing through chamber 18. On the other hand, those electrons entering through opening 17 at a time when the electric field within the chamber 18 is of such polarity as to retard them will likewise emerge from the opening 19 when the polarity of the electric field there is such as to retard them. The electron stream is accordingly subdivided into alternate groups of higher velocity electrons and lower velocity electrons; and as these groups travel forward the electrons will tend to become segregated into "bunches"; in other words, the electron stream will have successive portions in which the electron density is high separated by portions in which the electron density is low.

It is likewise known in the art that by posi-

tioning an electrode of proper potential at a suitable distance outside the opening 19 of the resonant chamber the velocities of the electrons in the stream may be reversed, and the "bunches," or at least a substantial portion thereof, may be caused to re-enter the resonant chamber 18. By proportioning the distance of the reflector electrode so that electric field in the chamber 18 opposes this reversed velocity at the time the bunches or concentrated portions of the electron stream thus pass in the reverse direction through the chamber 18, the electrical vibrations in the latter are reinforced. By suitable arrangements too well known in the art to require description here, electrical energy may be withdrawn for use in external circuits at the frequency of the vibrations thus maintained in the chamber 18.

It has been found however, in the prior art that with reflector electrodes heretofore known a very substantial fraction of the electrons whose velocity is reversed by the reflector electrode failed to re-enter the chamber 18 but by straying radially outward are deflected to the exterior surface of the chamber. In Fig. 1, however, I show a type of reflector electrode which is an improvement on those of the prior art in which it makes possible the regulation of the electric field between the reflector electrode and the opening 19 in such a way as to decrease the fraction of the reflected electrons which fail to re-enter chamber 18 through opening 19. I have discovered a number of different forms for the reflector electrode which produce improved results over those of the prior art and thus are shown respectively in Figs. 1, 2, 3 and 4.

Referring in detail to the reflector electrode shown in Fig. 1, it comprises what may be considered to be a spherical surface subdivided by narrow insulating gaps into three sectors or zones 23, 24 and 25, the above mentioned insulating gaps being respectively shown at 26 and 27. Each of the sectors 23, 24 and 25 is connected by a suitable lead-wire to sliders on the potentiometer 20. By adjusting the position of the last mentioned sliders, the form of the electric field inside the reflector electrode and between its adjacent end and the opening 19 can be varied at will to a considerable degree.

In particular it will be noted that if the three sliders connected respectively to the sectors 23, 24 and 25 are positioned at the same point on the potentiometer 20, the electric potential of the zones 23, 24 and 25 are the same and the zones 23, 24 and 25 thus constitute what is in substantial effect a single spherical surface with an opening aligned with the opening 19 in chamber 18. Preferably the diameter of the spherical surface thus produced is substantially greater than that of the opening 19 so that the spherical surface subtends a solid angle at the center of the sphere which is substantially greater than 2π solid radians. I have found that a reflector electrode of the spherical type thus produced gives very satisfactory results in producing an electric field between its outlet and the grid 19 of such form as to ensure that a large fraction of the reflected electrons re-enter the chamber 18.

However, I have also found that the configuration of the last mentioned electric field which gives optimum re-entry of electrons into chamber 18 depends on the value of the current flowing from cathode 14 through chamber 18 and on other electrical and geometrical parameters of the structure so far described. On that account, it is desirable in the case of some types of

reflex oscillator to adjust the sliders on potentiometer 20 so as to set up differences of potential between the sectors 23, 24 and 25. It is possible to determine the positions to be taken by the potentiometer sliders experimentally to give the highest efficiency of the reflex oscillator; and it is also possible by calculation or suitable experiments to determine the configuration of the electric field between the reflector electrode and the grid 19, and similarly to determine the potentials to be applied to the sectors 23, 24, 25 which will give such optimum configuration by calculation or experiment.

In Fig. 2 I show an alternative form for the reflector electrode which may comprise a cylindrical chamber having a plane end wall 31, cylindrical side walls 32 and a second end wall 33 having an opening aligned with the grid 19. Suitable lead wires from the wall portions 31, 32, and 33 lead to sliders on the potentiometer 20 so that the electrical potentials of the wall portions may be adjusted at will. In particular, it will be obvious that when the three sliders connected to the wall portions 31, 32 and 33 are positioned at the same point on the potentiometer 20 the chamber of Fig. 2 will constitute, in effect, a cylinder with equipotential walls having an opening at one end aligned with the grid opening 19.

In Fig. 3 I show still another form of reflector electrode which may be considered to comprise roughly a truncated cone having a base portion 34 with an opening aligned with the opening 19 and having its curved surface divided into two portions 35 and 36 preferably of equal area by a plane passing through the axis of the cones. Each of the zones 34, 35 and 36 is connected by a suitable lead with the potentiometer 20. It will again be obvious that when the potentiometer sliders connected to these leads are placed on the same portions of the potentiometer 20 the reflector electrode will, in effect, comprise a truncated cone having an equipotential surface. It will be noted that if the potentials of the portions 35 and 36 are given different values, the electric field between them and the opening 19 will be dissymmetrical about the axis of the chamber 18.

It will be obvious that both the Fig. 2 and the Fig. 3 reflector electrodes may be considered to comprise surfaces which subtend about a point in their central region a solid angle greater than 2π solid radians.

It is, of course, possible to obtain reflector electrodes which are less flexible electrically to adjustment by omitting either of the gaps 26 or 27 in Fig. 1, or the analogous gaps in Figs. 2 and 3. I have also found that a very useful reflector electrode results if the zone 33 in Fig. 2 is omitted from the reflector electrode surface thereby giving a reflector electrode of the type shown in Figs. 4 and 5. A moment's consideration will show that if the electrode 31 is given a less positive potential relative to the electrode 32, the electrical field in the vicinity of the opening 19 will have equipotential lines in the general form of the dotted lines 37 in Fig. 4. On the other hand, if the sector 31 is given a more positive potential the equipotential surfaces will have the form shown by the dotted lines 38 in Fig. 5. Figs. 4 and 5 thus illustrate the general character of the alteration of the electric field in the region between the reflector electrode and the opening 19 which results from adjusting the relative potentials of the sectors of the reflector electrode surface.

While I have illustrated the principles of my

invention by showing specific embodiments thereof, these principles are of broader application in ways which will be evident to those skilled in the art.

I claim as my invention:

1. Means for producing an electron beam, a cavity resonator mounted along the path of said beam and having conducting walls provided with openings to be traversed by said beam, and a reflector electrode aligned with said openings and comprising a hollow member having walls which subtend, about a point in the central region of the member, a solid angle substantially greater than 2π solid radians, said walls having an opening in the path of said beam.

2. A reflector electrode for an oscillation generator of the reflex type which comprises a hollow sphere having an opening in its surface said surface subtending, about a portion in the central region of said chamber, a solid angle substantially greater than 2π solid radians.

3. A reflector electrode for an oscillation generator of the reflex type comprising a hollow body having a surface of conducting material subdivided into a plurality of zones insulated from each other, and having an opening in the surface of one said zone, the surface of said reflector electrode subtending, about a point in the central region of said reflector electrode, a solid angle substantially greater than 2π solid radians.

4. A reflector electrode for an oscillator of the reflex type comprising a spherical surface having an opening therein and subdivided in a plurality of zones insulated from each other.

5. A reflector electrode for an oscillator of the reflex type comprising a spherical surface having an opening therein and subdivided in a plurality of zones insulated from each other, the surface of said reflector electrode subtending, about a point in the central region of said re-

flector electrode, a solid angle substantially greater than 2π solid radians.

6. A reflector electrode for an oscillation generator of the reflex type comprising a hollow cylindrical wall of conducting material, an end wall at one end thereof of conducting material and insulated from said cylindrical wall, and adjustable means connected to said walls for varying the relative electrical potentials of said end wall and said cylindrical wall.

7. An electronic device comprising means for producing an electron beam, a cavity resonator mounted along the path of the beam, said resonator having conducting walls provided with openings to be traversed by the beam, and a reflector electrode aligned with the openings, said reflector electrode comprising a hollow member having a substantial maximum inner cross-sectional area and having an opening in its wall portion which has an area smaller than the maximum cross-sectional inner area of the hollow member transverse to the path of the beam, the last named opening being adjacent an opening of the resonator.
